UNITED STATES PATENT OFFICE.

THEODORE H. CURTIS, OF CLEVELAND, OHIO.

SLAUGHTERING APPARATUS.

SPECIFICATION forming part of Letters Patent No. 448,413, dated March 17, 1891.

Application filed October 28, 1890. Serial No. 369,580. (No model.)

To all whom it may concern:

Be it known that I, THEODORE H. CURTIS, of Cleveland, in the county of Cuyahoga and State of Ohio, have invented certain new and useful Improvements in Slaughtering Apparatus; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

This invention relates to certain improvements in slaughtering apparatus.

The object of the invention is to provide improved means for catching and elevating hogs which will grasp the animal by two legs and securely hold the animal against twisting or wrenching either leg loose, and which can be easily and quickly operated.

A further object is to provide improved catching and elevating apparatus which can be operated by one person, and which has two connected grapples operated by two handles, and improved means whereby the hog can be released when desired.

These objects are accomplished by and this invention consists in certain novel features of construction and in combinations of parts more fully described hereinafter, and particularly pointed out in the claims.

Referring to the accompanying drawings, Figure 1 is an elevation showing the grapples closed, parts being broken away. Fig. 2 is an edge view, the device being closed. Fig. 3 is an elevation showing the grapples opened in position to grasp the legs of the hog, parts being broken away. Fig. 4 is a detail section on line $\alpha\alpha$, Fig. 1, showing the locking-bolt and means for operating the same to open the grips or grapples.

In the drawings, the reference-letter a indicates the carrying or connecting frame of the device, preferably formed integral of suitable metal and of sufficient strength to support a hog, and at one end having the two opposite extending bearing-arms b b , which carry two similar grips or grapples or other means to hold the hog. Each grapple consists of the main operating-lever c , strongly

pivoted a distance from its grasping end to an arm b to swing laterally and having its opposite end extended to receive a handle e . The short lever member f of the grapple is strongly pivoted on the main lever at a^2 in rear of the pivotal point d , (to receive its power,) while the rear end of said short lever is fulcrumed to the outer end of a pivoted link g , extending toward the center of the frame and at its inner end loosely secured to the frame, so as to oscillate as the levers move. The outer or grasping ends of the lever members of each grapple are oppositely curved, respectively, outwardly and then inwardly, and the end of one lever is longitudinally bifurcated at h to receive the end of the other lever, which extends therethrough when the levers are closed with their ends overlapping.

From the foregoing it will be clearly evident that when the two operating levers or handles of the two grapples are swung in certain directions the grapples will be closed, and when swung in the opposite directions they will open by reason of the peculiar arrangement and pivotal union of the two different classes of levers embodied in each grip, the main lever operating the short lever. In the present design of carrying out my invention when the two lever-handles are moved toward each other the levers close and when moved away from each other they open; but of course the arrangement might be varied so that the grips would close and open when moved oppositely from the manner described above. Certain means are also provided for locking the grapples in their closed positions, each grapple being provided with separate and independent means as follows: The rear end of the frame is provided with a pair of oppositely-extending arms i i , projecting over the operating-handles and provided on their rear sides with outwardly and oppositely inclined ratchet-teeth j , and each operating-lever has a lateral lug i^2 , upon which a dog k is mounted, provided with engaging-shoulder l to slide over the ratchet-teeth of its arm i when the lever is thrown in to close the grips, (under influence of spring l' ,) but to tightly bite into and mesh with said teeth against outward movement of the levers to open the

grips, thereby firmly locking the same. These dogs have the extended handle ends l^2 conveniently located, so that the operating-levers can be easily released and swung out by 5 merely pressing in the handle ends of the dogs with the thumbs while the levers are moved. Suitable stops are provided for the dogs.

The inner ends of pivoted links g may be 10 provided with longitudinal slots m , and said ends extend through the walls of a box or casing n , formed longitudinally on the frame. The links are confined by pins o , passing through the frame and said slots, thereby allowing limited longitudinal play thereof. A bolt p is longitudinally movable in said box or casing and extends rearwardly beyond the frame and has elevating chain or connection q attached strongly to its outer end. The 15 longitudinal movement of the bolt is limited by a longitudinal slot u and a pin v , secured to the frame and extending therethrough. Within the box or casing the bolt fits snugly and is provided on two sides with the laterally-inclined faces or steps 1^2 to bear against the ends of links g . The normal position of the bolt is that shown in Fig. 1, with the 20 grips closed, and one or more expansive springs a' are employed in the box to yieldingly hold the bolt in its normal position, with the ends of the links resting between faces 1^2 . A longitudinal slot is formed in said box or casing, and also an aperture b' is formed in said bolt.

35 The operation of the apparatus is as follows and will be readily understood by all persons acquainted with modern methods of 30 slaughtering hogs: A man is located in the pen, holding the present device by the handles with the grips open. He then catches a hog by the two hind legs and throws the handles toward each other, thereby firmly gripping the hog, while the locking devices before mentioned securely hold the grips locked. As soon 45 as the hog is securely caught the operator places the hook of the elevating-rope into ring c' , secured to hook d' of the chain q , and the hog is then elevated and placed on the tramway carriage or trolley by hook d' . When it is de- 50 sired to drop the hog, the handles are grasped and the locking-dogs pressed in and the handles thrown apart, thus opening the grips and releasing the animal's legs. When the construction of Fig. 1 is employed, the hog is ordi- 55 narily delivered by a tool, Fig. 4, consisting of a lever e' , which enters aperture b' of the bolt and has a swinging hook f' , which bears up against the lower end of the frame and forces the frame up independently of the 60 locking-bolt, whereby the ends of the links g are allowed to slide inwardly on the inclined surfaces 1^1 , (by reason of the weight of the animal on the grasping ends of the levers,) thereby allowing the grips to open sufficiently 65 to allow the legs of the animal to slide therethrough, and thus drop the animal.

It should be observed that in the construc-

tion of Fig. 1 the device and hog is upheld by the locking-bolt. Hence as soon as the weight of the hog is upheld by said bolt the 70 frame and grapples tend to draw down on the bolt, whereby the ends of links g engage outwardly-inclined surfaces 2^2 and are forced out thereby, and thus the grasping ends of the levers are tightened around the legs of the 75 animal. It should be understood that when the links g are moved outward the grasping ends of the same are drawn together, and vice versa when the links move in.

The construction shown in Fig. 3 dispenses 80 with the locking-bolt and co-operating parts, the links g being pivoted to lugs of the frame at 3^3 to allow oscillation of their outer ends, and the elevating-chain being secured directly to the end of the frame at 4 , the 85 device being otherwise the same as that of Fig. 1, only far simpler in construction. The animal is delivered by releasing the operating-levers and throwing them apart, as before described.

In slaughtering establishments hogs are ordinarily secured and raised by a chain shackled around one leg of the animal. The other leg is thus left free, allowing the animal to kick, wrench, and throw himself, thereby rupturing the blood-vessels at the joints and in the bones. This blood settles and cannot be cured, and hence a percentage of the 95 hams will not cure satisfactorily. These disadvantages are obviated by the use of my invention, for the animal is lifted by both hind legs and has no chance to kick and throw himself, and hence the hams and meat can be 100 thoroughly cured.

This invention consists, broadly, in a hog-grappling mechanism composed of two grapples (nor do I limit myself to a peculiar construction of grapple or grip) so positively or fixedly connected or secured together that they will be fixedly held a determined distance apart when grasping the legs of the hog, thereby composing what might be termed a "double grapple," as the device is really a single tool or instrument, the two grips or grapples of which are positively secured together.

I do not limit myself to any peculiar arrangement, combination, connection, support, or frame whereby the grapples or grips are composed and positively secured together.

120 My invention further consists in the two fixedly-connected grapples or a double grapple and the two operating devices or levers for opening and closing the grapples, whereby one man can operate the tool.

125 The term "fixedly" herein employed is particularly intended to apply to the grapples when closed and grasping the hog's legs, for when open the grapple members thereof might have some movement.

130 My invention further consists in a double grapple or two grapples having positive locking means for locking the grapples upon the legs of the hog.

Two loosely-connected grapples have heretofore been used to grasp the animal by both legs; but in practice two men are required to successfully apply them to the animal, and the grapples being only connected by ropes and held locked by the weight of the animal the hog is able to throw one leg loose and is left suspended by one leg, this old arrangement also possessing certain other disadvantages. The present device has its two grips fixedly connected, so as not to move independent of each other, with two handles to operate the same. The device can hence be operated by one man. The legs of the hog are firmly held, so that he cannot kick alternately with his hind legs. Each grapple has independent locking means, so that the grapples automatically lock the moment they are sufficiently applied and can be released instantly. One grapple can tightly grasp and hold the small portion of one leg while the other grapple grasps the larger portion of the other leg. By reason of the peculiar shape of the grasping ends of the levers the legs of the animal are guided into the proper position to be grasped, and are thereby easily, quickly, and surely caught without danger of missing.

It is evident that various changes might be resorted to in the form and arrangement of the parts described without departing from the spirit and scope of my invention. Hence I do not wish to limit myself to the construction herein set forth, but consider myself entitled to all such changes and modifications as fall within the spirit and scope of my invention.

What I claim is—

1. A device for the purpose mentioned, having two lever-grips held a fixed distance apart.
2. A hog grappling and elevating mechanism comprising the two pivoted lever grips or grapples so arranged and positively connected or secured together as to be rigidly held a fixed distance apart when locked upon the legs of the hog, and thereby holding said legs rigidly together, substantially as described.
3. A hog grappling and elevating mechanism comprising a pair of grapples or grips, positive non-flexible connections between said grapples, and a pair of operating levers or handles, each grip having but one of said operating levers or handles, whereby one man can operate both grips, and the grips will rigidly hold the legs of the hog.
4. In a hog grappling and elevating mechanism, the combination of the two grapples, each having a single operating lever or handle, and positive locking means for said grapples, substantially as described.
5. In a hog grappling and elevating mechanism, the combination of the two grapples or grips, rigid connections between said grips, positive locking means therefor, and the single elevating chain or connection for support-

ing both grips, said connection being connected to the grips independent of said locking means and the operating-levers of the 70 grips.

6. In a hog grappling and elevating mechanism, the combination of the two grapples or grips, rigid connections between the grips, two operating levers or handles, and the elevating chain or connection attached to the connections between said grips independent of said operating-levers. 75

7. In a hog grappling and elevating mechanism, a lever-grip, the outer ends of the grip-levers being flared or bent outwardly and made to overlap when closed, as set forth. 80

8. The combination, with a connecting-frame, of two lever-grips pivoted to and fixedly connected thereby, substantially as described. 85

9. In a device for the purpose mentioned, a frame, in combination with a grip composed of levers of two different classes, one lever being pivoted to the frame and pivoted to 90 and operating the other, substantially as described.

10. A hog-grappling mechanism comprising, in combination, the two positively and fixedly connected lever-grips, each having a 95 single operating-lever, whereby one man can operate the two grips, substantially as described.

11. In combination, a rigid frame to which the elevating-chain is connected and the grips 100 pivoted thereto and having two operating-levers, substantially as described.

12. In a device for the purpose mentioned, one or more grips and independent locking means for each grip, whereby each grip can 105 be independently locked at any position or released, substantially as described.

13. The grips composed of levers, in combination with a separate independent locking-dog for the operating-lever of each grip and 110 a frame connecting said grips, and with which said dogs engage to lock the grips.

14. In combination, the frame having ratchet-teeth, lever-grips carried by the frame, each having an operating-lever, and pivoted dogs 115 carried by said levers to mesh with said teeth and lock the grips.

15. A grip mounted on a frame and having a swinging operating-lever, and a pivoted spring locking-dog carried by said lever, arranged to engage the frame and lock the lever and be operated by the thumb to release the lever. 120

16. A hog grappling and elevating mechanism comprising a pair of lever-grips, grapples, 125 or other means to grasp and hold both hind legs of a hog held a fixed distance apart when closed and locked upon the legs of the hog, substantially as described.

17. In combination, a frame, a pair of grips 130 composed of levers, and a movable bolt mounted in the frame and to which the elevating-chain is attached, said bolt being arranged when upholding the hog to tighten said grips

and when the frame is lifted thereon to partially open the grips, substantially as described.

18. In combination, the frame having a longitudinal opening, the bolt longitudinally movable therein and to which the elevating-chain is attached, said bolt having steps or inclined surfaces, as set forth, and the grips composed of the levers, one lever of each grip having a link, as set forth, to bear against said bolt and be operated by the steps or inclined faces thereof, substantially as described.

19. In combination, a frame and a grip carried thereby, consisting of an operating-lever fulcrumed on the frame, one end forming a handle and the other a grasping end, and another short lever at one end movably fulcrumed to the frame, the other end forming a grasping end, said lever being pivoted between its ends on the operating-lever, substantially as described.

20. In a catching and elevating apparatus, a pair of grips or grapples arranged so as to be held a fixed distance apart when locked and to grip both hind legs of a hog and prevent independent movement thereof and locking means to hold said grapples rigidly closed or locked, substantially as described.

21. In a hog grappling and elevating mechanism, the combination of the two grapples and positive connections between the same so arranged and constructed that the grips are fixedly held a determined distance apart when grappled upon the hog's legs, substantially as described.

22. A hog-catching tool consisting of the double grip or grapple, the grapples of which

are relatively fixed, substantially as and for the purposes set forth.

23. A hog-catching tool consisting of the double grapple and the two operating-levers to close and open the grapples of said tool, substantially as described.

24. A hog-catching tool consisting of the double grapple, the operating-levers to close and open the grapples thereof, and locking means to lock the grapples upon the legs of the hog, substantially as described.

25. A hog-catching tool consisting of a rigid support and two grapples carried thereon, substantially as described.

26. A hog-catching tool consisting of two grapples fixedly secured together and incapable of relative independent movement and a single supporting or elevating chain or connection, substantially as described.

27. A hog-catching tool composed of two fixed grapples arranged and constructed to grasp both hind legs of a hog and rigidly hold them against independent movement and means for opening and closing said grapples, substantially as described.

28. A hog-catching tool consisting of two grapples, means for operating the same, and positive connections or a non-flexible support between the grapples, substantially as described.

In testimony that I claim the foregoing as my own I affix my signature in presence of two witnesses.

THEODORE H. CURTIS.
